CLAIM

The ornamental design for a golf shoe sole, as shown and described.

DESCRIPTION

FIG. 1 is a perspective view of the golf shoe sole showing our new design;

FIG. 2 is a bottom plan view thereof;

FIG. 3 is a front elevational view thereof;

FIG. 4 is a rear elevational view thereof;

FIG. 5 is a side elevational view thereof; and,

FIG. 6 is an opposite side elevational view thereof.

The broken lines showing a shoe upper in FIGS. 1—6, the broken lines showing golf cleats in FIGS. 1, 3—6, and the broken lines showing a logo in FIGS. 1 and 3 are for illustrative purposes only and form no part of the claimed design.
